UNITED STATES PATENT OFFICE.

JOHN J. LOVE, OF NEW YORK, N. Y.

IMPROVED DOUBLE-HEADED WRENCH.

Specification forming part of Letters Patent No. 59,242, dated October 30, 1866.

To all whom it may concern:

Be it known that I, JOHN J. LOVE, of city, county, and State of New York, have invented a new and useful Improvement in Double-Headed Wrenches; and I do hereby declare that the following is a full, clear, and exact description thereof, which will enable others skilled in the art to make and use the same, reference being had to the accompanying drawings, forming part of this specification, in which—

Figure 1 is a side view of my improved wrench. Fig. 2 is a cross-section of the same, taken through the line *x x*, Fig. 1.

Similar letters of reference indicate like parts.

My invention has for its object to furnish an improved wrench, simple in construction, easy of adjustment, and strong; and it consists of the combination of a right-and-left screw with the parallel moving bars having the jaws of the wrench on their ends, the parts being constructed and arranged as hereinafter more fully described.

A and *B* are the bars of the wrench, upon the outer ends of which are formed the outer jaws, *a*¹ and *b*¹, of the wrench-heads, which, when the bars are placed in position upon each other, point in opposite directions, as shown. Part of these bars *A* and *B*, on the edges that are toward each other, are cut away, as shown in Fig. 1, and from the shoulders thus formed the bars are perforated longitudinally, and have screw-threads cut in the holes thus formed for the reception of the right-and-left screw *C*.

Upon the inner ends of the bars *A* and *B* are formed the other jaws, *a*² and *b*², of the wrench-heads. To the sides of the jaws *a*² and

*b*² are welded or otherwise securely attached the ends of broad straps *a*³ and *b*³, which pass around and fit closely to the larger parts of the bars *A* and *B*, as shown in Figs. 1 and 2, and through which the said bars slide as they are moved back and forth by the screw *C*. The screw *C* has a right screw-thread cut upon one of its ends, and a left screw-thread upon the other end, which threads fit into the screw-threads of the holes formed in the bars *A* and *B*, as before described.

Upon the middle part of the screw *C* is formed a small cylinder, *c*', by means of which the said screw is operated. The surface of the cylinder *c*' is milled, to enable it to be more readily turned. By turning the screw *C* in one direction the jaws of both heads are moved apart or opened, and by turning it in the other direction the said jaws are closed.

To enable the wrench to more readily take hold of nuts in all situations the faces of the jaws of one head are made at right angles to the direction of the bars *A* and *B*, and the faces of the jaws of the other head are inclined outward, as shown in Fig. 1.

I claim as new and desire to secure by Letters Patent—

An improved wrench, formed by the combination of the right-and-left screw *C* with the parallel-moving bars *A* and *B*, having the jaws *a*¹ and *a*² and *b*¹ *b*² formed upon their ends, the parts being constructed and arranged substantially as herein described, and for the purpose set forth.

JOHN J. LOVE.
